UNITED STATES PATENT OFFICE

122,796

DESIGN FOR A TELEPHONE SWITCHBOARD

Frederic S. Grover, Rochester, N. Y., assignor to
The Stromberg-Carlson Telephone Manufacturing Co., Rochester, N. Y., a corporation of
New York

Application August 3, 1940, Serial No. 94,132

Term of patent 14 years

To all whom it may concern:

Be it known that I, Frederic S. Grover, a citizen of the United States, residing at Rochester, in the county of Monroe and State of New York, have invented a new, original, and ornamental Design for a Telephone Switchboard, of which the following is a specification, reference being had to the accompanying drawing, forming part thereof.

The figure is a perspective view of a telephone switchboard showing my new design.

It will be understood that the right-hand side or end of the switchboard which is not visible in the drawing, is substantially similar to the visible left-hand side or end thereof.

I claim:

The ornamental design for a telephone switchboard, substantially as shown and described.

FREDERIC S. GROVER.
